UNITED STATES PATENT OFFICE

JERRY T. SMITH, OF WASHINGTON, DISTRICT OF COLUMBIA

ROLLER SKATE

Application filed April 10, 1930. Serial No. 443,112.

This invention relates to roller skates.

The primary object of this invention is to provide, in a manner as hereinafter set forth, a roller skate embodying a base plate and a 5 foot plate mounted for relative reciprocation, and further embodying a gearing mechanism actuated by the reciprocation of the plates and operatively connected with the ground wheels of the skate for imparting motion to 10 the latter.

A further object of the invention is to provide a skate of the type aforesaid wherein a housing is provided for the gearing mechanism to protect the latter and to provide for 15 proper and constant lubrication thereof.

A further object of the invention is to provide a roller skate of the character aforesaid in which the relative movable plates of a pair of skates may be reciprocated alternately 20 by the stroking action of the user, or in which the relative movable plates may be reciprocated in unison by means of the alternate shifting of the weight of the user from toes to heels.

25 With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope 30 of the claims hereunto appended.

In the drawings in which like numerals are employed to designate like parts throughout the same:—

Figure 1 is a longitudinal section through a 40 skate constructed in accordance with this invention.

Figure 2 is a side elevation thereof.

Figure 3 is a fragmentary bottom plan thereof.

45 Figure 4 is a section taken on the line 4—4 of Figure 1.

Figure 5 is a section taken on the line 5—5 of Figure 1.

50 Figure 6 is a section taken on the line 6—6 of Figure 1.

Referring to the drawings in detail, the numeral 1 designates a foot plate having an adjustable toe portion 1' from which depends, in spaced relation to the forward end thereof, a bracket 2 for supporting the front 55 axle 3 upon which the front wheels 4 are mounted. At the rearward end thereof the plate 1 is formed with a vertically disposed web 5 which is of arcuate contour, open at its top and bottom, and extending above and below the plate 1. The plate is adapted to be secured to the foot of the user by means of a strap 6 carried by the web 5 and passing around the instep of the user, and by means of a suitable toe clamp 7 secured to the toe 60 portion 1' adjacent the bracket 2.

Pivoted to the under surface of the plate 1, adjacent the toe portion 1', is a base plate 8, the rearward end of which terminates adjacent the web 5 within the vertical wall of the 70 latter. Interposed between the plates 1 and 8, and disposed within the web 5, is a coiled spring 9 which normally maintains the rearward ends of the plates 1 and 8 in spaced relation as illustrated in Figure 1. 75

Secured to the lower surface of the base plate 8 is a housing 10 formed of an upper section 11 and a lower section 12. The upper section 11 includes a top wall 12' and a side wall 13 and is open at its bottom. The 80 section 11 is secured in position on the plate 8 by means of a plurality of holdfast devices 14 extending through the wall 12' and plate 8. The side wall 13 is inwardly offset at the sides of the section 11 whereby the upper portion 13' of the section 11 is reduced in width and is of less width than the plate 8. The offset in the side wall 13 is indicated at 85 14' and is disposed at a slight downward and rearward inclination. 90

The lower edge of the side wall 13 inclines at a downward and rearward inclination. The lower section 12 is formed with an open top and is secured to the upper section 11 by means of suitable holdfast devices 15 which 95 extend through lugs 16 projecting outwardly from the section 12 and further through similar lugs 17 projecting outwardly from the section 11 and in registry with the lugs 16. Preferably a suitable gasket, not shown, 100

will be interposed between the sections 11 and 12 in order that a fluid-tight connection may be provided therebetween.

Extending through and projecting from the sides of the housing 10 is a rear axle 18 upon which the rear wheels 19 of the skate are mounted. The axle 18 passes through registering recesses 20 and 21 respectively formed in the lower edges of the section 11 and the upper edges of the section 12. Adjacent the sides of the housing, the axle is provided with a race member 18', upon which the housing is supported by means of bearings 19' which are formed with flanges 20' rigidly secured to the upper section 11 of the housing. The bearings are further provided with adjustable caps 21' which are secured to the bearings by suitable bolts 22 extending through corresponding apertured lugs 22' formed on the bearings and caps.

Rotatably mounted on the axle 18 is a hub 23 for a pinion 24 and a gear 25 both of which are preferably formed integrally with the hub 23. One end of the hub 23 projects, as at 26, for engagement with one of the bearings 19'. A hub 28 for a pinion 29 is mounted on the shaft 18 to rotate therewith, preferably having a pin 30 extending through the hub and into the shaft.

Forwardly of the registering recesses 20 and 21, the lower edges of the section 11 and the upper edges of the section 12 are formed with registering recesses 31 and 32 within which is mounted a stub-shaft 33. Rotatably mounted on the shaft 33 is a hub 34 for a pinion 35 and a gear 36. The pinion 35 and gear 36 are preferably formed integrally with the hub 34 and the latter projects, as at 37, for abutment with the wall of the section 12 at one side of the latter in order to properly space the gear 36 and pinion 35 from such wall to bring the pinion 35 into mesh with the gear 25, and to bring the gear 36 into mesh with the pinion 29.

Interposed between the hub 34 and the wall of the section 12 at the opposite side of the latter is a hub 38 which is rotatably mounted on the shaft 33. Mounted on the hub 38, preferably integrally therewith, is a ratchet wheel 39 and a gear 40. The gear 40 is in mesh with the pinion 24 and the ratchet wheel 39 is adapted to have its teeth 41 engaged by the teeth 42 of a ratchet bar 43 depending from the foot plate 1. The ratchet bar 43 is formed at its upper end with a ball 44 which is seated in a socket forming member 45 secured to and depending from the lower face of the foot plate 1.

In vertical alignment with the member 45, the base plate 8 is provided with an opening 48, and, stamped from the top wall 12' of the upper section of the housing is a pair of downwardly extending guides 46 and 47, which provide an opening registering with the opening 48 through which the ratchet

bar 43 slidably extends. Secured to and depending from the guide 47 is a leaf spring 49 which bears against the rearward face of the ratchet bar 43 to maintain the teeth 42 of the latter in engaging position with respect to the teeth 41 on the ratchet wheel 39.

The web 5 is provided at each side thereof with a pair of spaced tongues 50 which are bent to extend inwardly beneath the base plate 8 at the side edges of the latter for abutment against the lower face of the plate 8 to provide stops for limiting the relative diverging movement between the plates 1 and 8.

In the operation of my improved roller skates, the foot plate 1 is normally maintained in its elevated position with respect to the base plate 8 by means of the coiled spring 9. When the weight of the user is shifted to the heel portion of the foot plate 1, the latter is depressed against the action of the spring 9 whereby the ratchet wheel 39 is rotated by the engagement of the ratchet bar 43 therewith. The gear 40 is rotated in unison with the ratchet bar 39 and drives the pinion 24 rotatably mounted on the axle 18. The gear 25 is rotated in unison with the pinion 24 and drives the pinion 35 with which the gear 36 rotates in unison to drive the pinion 29 fixedly mounted on the axle 18 to rotate the latter. The gears and pinions are constantly lubricated by a suitable lubricant contained within the housing 10.

By stroking in the usual manner, the user may alternately operate the skates of a pair in a manner as above described, or, if desired, he may operate the skates of a pair simultaneously by omitting the stroking action and by alternately shifting his weight from toes to heels. Upon the shifting of the weight of the user to his toes, the spring 9 operates to swing the foot plate 1 away from the base plate 8, and upon the weight of the user being shifted back to the heels, the foot plate 1 is moved toward the base plate 8 to operate the gearing mechanism as above described. The ratchet bar 43 is provided at its sides with longitudinally extending guides 52 which project forwardly of the teeth 42 into overlapping engagement with the ratchet wheel 39 at the side faces of the latter to maintain the ratchet bar 43 in alignment with the ratchet wheel 39 longitudinally of the skate whereby the leaf spring 49 will maintain the teeth 42 of the ratchet bar 43 in constant mesh with the teeth 41 of the ratchet wheel 39. Owing to the pitch of the teeth 41 and 42, the ratchet wheel 39 will be rotated upon the downward movement of the ratchet bar 43, while on the upward movement of the latter, the teeth 42 will slide over the teeth 41.

It is thought that the many advantages of a roller skate in accordance with this invention will be readily apparent, and al-

though the preferred embodiment of the invention is as illustrated and described, it is to be understood that changes in the size, shape and arrangement of parts may be resorted to, so long as such changes fall within the scope of the invention as defined in the appended claims.

What I claim is:

1. In a roller skate, a pair of plates mounted for relative reciprocation, a housing secured to one of said plates, a web carried by the other of said plates, a rotatable axle upon which the housing is mounted and provided with a ground wheel, a tension element normally forcing said plates apart, said plates being relatively movable toward each other against the action of the tension element, tongues formed on the web and extending beneath the plate to which the housing is secured to provide stop means for limiting the diverging movement of the plates, gearing mechanism mounted within the housing for driving the axle, and means operable by the relative reciprocation of said plates for actuating the gearing mechanism.

2. In a roller skate, a pair of plates mounted for relative reciprocation, a housing secured to one of said plates and having a portion thereof of less width than the plate which it is secured, a web carried by the other of said plates, a tension element interposed between the plates for normally forcing them apart, said plates being relatively movable toward each other against the action of the tension element, tongues formed on the web and extending beneath the plate to which the housing is secured to provide stops for limiting the diverging movement of the plates, a rotatable axle upon which the housing is mounted, gearing mechanism mounted within the housing for driving the axle, and means operable by the relative reciprocation of said plates for actuating the gearing mechanism.

45 In testimony whereof, I affix my signature hereto.

JERRY T. SMITH.
